(57) **CLAIM**

The ornamental design for a gutter guard, as shown and described.

DESCRIPTION

FIG. 1 is a top isometric view of a gutter guard showing the new design;

FIG. 2 is a top plan view thereof;

FIG. 3 is a right side view thereof;

FIG. 4 is a left side view thereof;

FIG. 5 is a bottom plan view thereof;

FIG. 6 is a front view thereof; and,

FIG. 7 is a rear view thereof.

FIGS. 1, 3, 4, 5, and 6 are shown with a symbolic break in the gutter guard's length. Any portion of the article between the break lines forms no part of the claim.

1 Claim, 6 Drawing Sheets Fig. 5
